UNITED STATES PATENT OFFICE.

ALBERT H. GAESS, OF WATERBURY, CONNECTICUT, ASSIGNOR TO THE E. J. MANVILLE MACHINE COMPANY, OF WATERBURY, CONNECTICUT, A CORPORATION OF CONNECTICUT.

FRAME CONSTRUCTION FOR METAL-HEADING MACHINES.

1,372,133.

Specification of Letters Patent. Patented Mar. 22, 1921.

Application filed April 1, 1920. Serial No. 370,408.

To all whom it may concern:

Be it known that I, ALBERT H. GAESS, citizen of the United States, residing at Waterbury, in the county of New Haven 5 and State of Connecticut, have invented a new and useful Improvement in Frame Construction for Metal-Heading Machines, of which the following is a specification.

This invention relates to those machines 10 for forming heads on metal blanks, of the class illustrated and described in U. S. patent to Andrew C. Campbell, No. 926,170, June 29, 1909, and more particularly to such machines of this class as have caps 15 which are hinged to the frames and swing over onto the tops of the dies for holding them in place, of the type set forth in U. S. patent to Albert H. Gaess, No. 1,166,668, of January 4, 1916.

20 Machines of this character are large and massive, they are required to operate rapidly upon tough metal of thick cross-section and of necessity the heavy reciprocating punch mechanisms strike powerful blows 25 upon the metal held in the dies. Consequently the frames of these machines are subject to great strains and tend to yield in the directions of least resistance under the impact of the blows of the punches on 30 the metal being shaped, yet the mechanisms must move easily and smoothly to reduce the motive power required to a minimum and must work exactly to produce an accurate and uniform product.

35 The object of this invention is to cause such coöperation between the frames and swinging die caps of these machines that the die caps besides providing means which permit easy and quick access to and secure an accurate retention of the dies, without complication and in a simple manner, tie together and strengthen the frames in their previously weakest localities, when secured in position for retaining the dies, and thus increasing the efficiency of the machines and uniformity of the product.

40 This object is attained in the embodiment of the invention illustrated by having sections of the upper surface of the frame 50 of the machine on each side of the die opening raised above the surrounding surface and forming on the outer edges of the raised portions upwardly extending shoulders that are parallel with the side walls of the die

opening in the frame, and providing the 55 side edges of the swinging die cap with downwardly extending shoulders that closely fit the shoulders on the frame so that when the cap is turned down and secured in operative position it forms a tie across the 60 space above the die opening and with the frame boxes in the die opening on four sides so that the frame cannot spring any more in one direction than the other under the impact of the blows of the reciprocating 65 punch mechanism.

Figure 1 of the accompanying drawings shows a plan of the frame of a machine of the class mentioned constructed according to this invention with a swinging die cap secured in operative position. Fig. 2 shows a central longitudinal section of the frame and die cap. Fig. 3 shows a transverse section of the frame on the plane indicated by the dotted line 3—3 on Fig. 1 with the die cap 70 closed. Fig. 4 is a plan of a portion of the top of the frame without the die cap. Fig. 5 is a view of the under side of the die cap.

The frame 1 is a massive integral casting of iron, oblong in outline, and provided near one end with the usual die opening 2 at the bottom of which is the die bed 3 that extends across from one side to the other of the die opening and is integral 85 with the frame. At each side of the die opening and raised somewhat above the top surface of the remainder of the frame in that locality is a rib 4. The outer vertical edges 5 of these ribs are machined substantially parallel to the side walls 6 of the die opening. On the top of the frame at the back end of the die opening is an integral boss 7 with a perforation that extends transversely of the frame and substantially 90 parallel to the back wall 8 of the die opening.

The die cap 9 has two perforated ears 10 that fit the boss on the frame and are hinged thereto by the pivot pin 11. The die cap 100 is swung over onto the top of the frame to permit access to the die opening and is turned down for closing the top of the opening and retaining the dies on the die bed. On the edges of the die cap are downwardly 105 extending flanges 12. The inner edges 13 of these flanges are machined substantially vertical parallel with the side walls of the

die opening and such a distance apart that when the die cap is turned down into the opening these inner edges of the flanges closely fit the outer vertical edges 5 of the 5 ribs 4 on the top of the frame, thus forming a clamp across the top of the die opening which prevents the frame from yielding outwardly on the top under the impulse of the powerful blows of the punching 10 mechanism of the machine when in operation. Bolts 15 are passed through the die cap into the ribs on the frame for holding the die cap down in position for closing the die opening on top and strengthening the 15 frame. With this construction the die cap coöperates with the frame in boxing in the die opening on all sides except the front and at the same time it clamps the top of the frame above the die opening so that it 20 cannot yield outwardly, the die bed joining the frame beneath the die opening.

The invention claimed is:—

1. A metal heading machine having a frame with a die opening and upwardly extending shoulders parallel with the side walls of the die opening, and a die cap connected with the frame and provided with downwardly extending shoulders parallel with the side walls of the die opening, said 25 downwardly extending shoulders on the die cap engaging the upwardly extending shoulders on the frame and preventing the frame from yielding outwardly when the die cap is in operative position and closes the top of the die opening.

2. A metal heading machine having a frame with a die opening, a die bed integral with the frame extending across the bottom of the die opening and upwardly extending 40 shoulders parallel with the side walls of the die opening, and a cap connected with the frame and provided with downwardly ex-

tending shoulders parallel with the side walls of the die opening, said downwardly extending shoulders on the die cap engaging the upwardly extending shoulders on the frame and tying the frame together above the die bed.

3. A metal heading machine having a frame with a die opening and upwardly extending shoulders parallel with the side walls of the die opening, and a cap hinged to the frame and provided with downwardly extending shoulders parallel with the side walls of the die opening, said downwardly extending shoulders on the die cap engaging the upwardly extending shoulders on the frame when the die cap is swung down into the die opening.

4. A metal heading machine having a frame with a die opening and upwardly extending shoulders at the sides of the die opening, a die cap hinged to the frame and provided with downwardly extending shoulders at its ends, said downwardly extending shoulders on the die cap engaging the upwardly extending shoulders on the frame when the die cap is swung down into the die opening, and means for securing the die cap with said shoulders in engagement.

5. A metal heading machine having a frame with a die opening and upwardly extending ribs parallel with the side walls of the die opening, a die cap hinged to the frame and provided with downwardly extending flanges parallel with the side walls of the die opening, the inner edges of said downwardly extending flanges on the die cap engaging the outer edges of the upwardly extending ribs on the frame when the die cap is swung down into the die opening, and means for securing the die cap with the shoulders engaging the flanges.

ALBERT H. GAESS.
